FIG. 1 is a top perspective view of a deck board fastener without the clip engaged;

FIG. 2 is a top perspective view of a deck board fastener with the clip engaged;

FIG. 3 is a bottom perspective view of a deck board fastener of FIG. 2;

FIG. 4 is a front view of a deck board fastener of FIG. 2;
FIG. 5 is a back view of a deck board fastener of FIG. 2;
FIG. 6 is a left side view of a deck board fastener of FIG. 2;
FIG. 7 is a right side view of a deck board fastener of FIG. 2;

FIG. 8 is a top plan view of a deck board fastener with the clip engaged of FIG. 2; and,

FIG. 9 is a bottom plan view of a deck board fastener of FIG. 2.

The broken lines in the drawings illustrate portions of the deck board fastener and form no part of the claimed design.
